POWER PRESS

Robert Temple, Jr., Denver, Colo., assignor to
 Robert Temple, Inc., Denver, Colo., a corpora-
 tion of Colorado

Application February 8, 1932, Serial No. 591,540

31 Claims. (Cl. 140—113)

This invention relates to power presses and its primary object is to provide a press employing as its motive agent, an explosive confined in a restricted chamber, to bring by its expansive force, a movable pressure element or hammer, into sudden and violent contact with the work. The present press as illustrated in the drawings and hereinafter to be described is especially adapted for forming joints between originally separated parts, and more particularly for the formation of bonding joints of electric transmission bars and wires or of other equipment requiring the bonding of sections of metallic conductors for the transmission of electric current. By the use of a press constructed in accordance with the present invention, an intimate bond is produced between metallic electric conductors and their couplings, which provides the mechanical strength necessary to sustain stresses to which the conductors are subjected and which insures the intimate electric contact between the coupling and the sections of the conductor necessary for the uninterrupted flow of current between them. It is to be understood, however, that while the press as shown is particularly designed for the above stated purpose, it may be effectively employed for other work in which a powerful and sudden movement of an impact element is an essential requirement.

A press of similar character has been shown and described in my application for patent Serial No. 557,857 filed August 18, 1931, and the present invention is directed to certain changes and improvements which increase the practicability and efficiency of the device.

As stated hereinbefore, the press is particularly adapted for joining conductors of electricity in a coupling-member, and the product of its operation in this respect has been shown and described in my co-pending application for patent Serial No. 562,754, filed September 14, 1931.

In the present application, the press has been designed to connect two conductors of electricity in end-to-end relation within a coupling-sleeve, by delivering a sudden and powerful blow upon the sleeve at opposite sides of a mediate point, thereby off-setting the sleeve and the wires within the same and at the same time widening the parts by lateral distortion. As a result of these actions, the wires are securely locked in the sleeve in intimate electrical contact with the same. Inasmuch as the product of the press has been fully described in the before-mentioned application for patent, the present invention will be un-

derstood, without further detailed description of the same.

In the accompanying drawings in the several views of which like parts are similarly designated, Figure 1 represents a vertical sectional elevation of the improved press,

Figure 2, a similar elevation in the plane indicated by the line 2—2 in Figure 1,

Figure 3, a transverse section along the line 3—3 of Figure 1,

Figure 4, a sectional view of the upper portion of the press, showing the firing element thereof in its inoperative position,

Figure 5, a vertical sectional view of a press of modified construction drawn to a larger scale,

Figure 6, a similar view in the plane indicated by the line 6—6 in Figure 5,

Figure 7, a fragmentary cross-section on the line 7—7, Figure 5, and

Figure 8, a transverse section taken on the line 8—8 of Figure 6.

Referring first to Figures 1 to 4 of the drawings, the press comprises a body or main frame 5 having in its lower portion a seat for a die or anvil 7. The press is at this point of bifurcated form and the anvil is placed upon its seat by sliding it between the leg-portions 8 of the press.

The anvil is subsequently clamped in place by means of tapering wedge-pins 9 driven into complementary grooves 10 of the leg portions and of a flanged base 12 embracing the ends of the same. The pins 9 and the base 12 thus provide a clamping element for securing the anvil in place between the legs of the frame. The anvil has a groove 13 to receive the coupling sleeve 14 of conductors of electricity 15 or other work, and the groove is formed in cross-section to correspond with the exterior shape of the work.

The frame or body 5 has above and as a continuation of the space between its parallel leg-members, a cylindrical bore 16 partially lined with a bushing 17 of acid resisting steel or other suitable metal. This bushing is mechanically fitted and pressed into the bore and it is flanged at its upper end to engage with a shoulder 18 of the bore. The provision of an acidproof bushing is an important factor since it prevents corrosion by products of the explosive gases.

Above the shoulder 18, the bore is screw-threaded to receive and secure the lower portion of a cylinder-head 19. The head has an axial bore 20 which in the operation of the press functions as an explosion chamber, the lower end of which is widened by a counterbore 21 to spread the expansive gases produced by an explosion in the

chamber 20 over the impact-surface of a piston 22 slidably fitted in the bushing of the cylinder.

This piston carries at its lower end an upper die or hammer 23 by means of screw-threads 24, and it has an axial bore 25, in which fits a spring-pressed pin 26 which in the operation of the press engages the work on the anvil at a medial point to hold it against displacement. The hammer engages the work at opposite sides of this point as clearly shown in Figure 2, and its work-striking faces 27 slant outwardly as best shown in Figure 2, to produce tapering indentations on the outside of the sleeve 14 and on the conductors 15, so that deeper shoulders and a wider spread 10 is produced adjacent the central portion of the sleeve and at the ends of the conductors.

This is a distinct improvement over the joints disclosed in the before mentioned earlier applications for patent, since it strengthens the lock 20 between the sleeve and the conductors and betters the intimate conductive contact of the conductors with the sleeve.

The pin 26, slidably fitted in the bore of the piston 22, is partially hollow to house a helical spring 28 which abuts against the breast of the bore of the piston, to hold the pin in contact with the work, and a stud 29 screwed into the piston projects into the spring to hold it against lateral deformation.

30 A packing-ring 30 between the bushing of the cylinder and the end of the cylinder head 19 provides for a gas-tight joint between the same.

The bore of the cylinder head is countersunk at its upper end as at 31, to support a cartridge 35 32 which in practice, occupies the upper portion of the explosion-chamber 20. This cartridge which constitutes the motive agent of the press, contains an explosive powder and above the same a detonating cap 33.

40 The cartridge is accurately fitted in the upper portion of the explosion chamber, leaving the lower portion thereof vacant for the expansion 45 of gases produced by the ignition of the explosive charge. The upper portion of the cylinder head, above the main frame of the press, is reduced in diameter and screw-threaded for a cap 34 which closes the explosion chamber and which has a hollow extension 35 closed at its upper end by a screw plug 36. The cap provides a carrier and 50 a housing for the firing mechanism of the press, which consists of a piston 37 slidably fitted in the interior bore of the extension 35, a stem 38 formed integrally with the piston 37, projecting through a central opening of the screw plug, and 55 a pin 39 at the lower side of the piston which in the operation moves through an aperture of corresponding size in the portion of the cap 34 at which it engages the piston-head 19, to forcibly engage with the detonating cap of the cartridge.

60 The forcible engagement of the firing pin 39 with the detonating cap 33 is effected by expansion of a helical spring 43 in the space between the piston 37 and the plug 36, which is compressed when the piston is moved outwardly to the position illustrated in Figure 4.

The piston stem 38 has at its upper end, a head 40 to facilitate its upward movement, and it is furthermore provided with a transverse aperture 41 to receive a cotter pin 42 which by engagement with the plug 36, holds the firing-element 70 of the press in an inoperative position as illustrated in Figure 4 of the drawings.

In the operation of the press, the coupling sleeve 14 of the conductors is placed between the 75 legs of the frame after the anvil 7 has been re-

moved therefrom. The anvil is then replaced upon its seat and clamped in place by means of the wedge-pins 9 which are driven into the complementary grooves of the legs 8 and the flanges of the base 12. The pin 26 under pressure of its spring 28 holds the work in place upon the anvil. The spring also holds the piston 22 up against the cylinder head 19 to insure its contact with the lower end of the piston head and thereby define the extent of the explosion-chamber 20.

After the piston 37 of the firing mechanism has been raised against the pressure of its spring 43 and held against retrograde motion by the cotter pin 42 in the aperture of its stem, as illustrated in Figure 4, the cap 34 is unscrewed from the piston head and the cartridge 32 is inserted into the upper end of the explosion chamber 20. The cap is then replaced and the press is ready for operation.

The operator now withdraws the pin 42 from the aperture of the stem 38 with the result that the spring 43 by its consequent expansion drives the pin 39 at the end of the piston 37 forcibly into contact with the detonating cap 33 of the cartridge 32. This action explodes and fires the powder-charge of the cartridge and the large volume of gases resulting from the explosion, by its expansive force, moves the piston 22 and the hammer 23 at the end thereof, downwardly with high velocity and brings the hammer into violent and sudden contact with the coupling sleeve on the anvil 7.

The sleeve 14 and the conductors 15 within the same are in consequence deformed and compressed at opposite sides of its mediate point engaged by the finger 26 with the result that the conductors are firmly fixed inside the sleeve and in intimate conductive contact with the same as hereinbefore explained.

40 The helical spring 28 acting upon the pin 26, holds the piston 22 and the hammer die 23 against operative motion until the desired or maximum amount of pressure is obtained from the explosive charge.

45 In the modified construction shown in Figures 5 to 8 of the drawings, the firing mechanism is at a side of the explosion chamber, and the hammer-carrying piston is held in its elevated position by frictional means. The finger holding the work in place on the anvil has been omitted. The press of the modified construction is particularly designed for compressing and bonding large size metallic bars, stranded cables and wires.

50 The anvil 44 of the modified press is held in place on its seat by tenons 45 on its under side slidably fitted in grooves 46 in the seat. This prevents the legs of the press-frame or body 5 from spreading apart. A hammer 47 is as before screw-fastened at the lower end of a piston 48 fitted for reciprocation in the bushed cylinder 49 of the press frame.

55 The piston 48 has at its upper end a taper bore 50 to receive in frictional contact with its wall a correspondingly formed plug 51 at the lower end of a piston 52 slidably fitted in the upper portion of the piston cylinder 49. The space 53 of the cylinder between the pistons 48 and 52 constitutes the explosion chamber of the press. The cartridge 54 is housed in a hollow gland 55 screwed into an opening at a side of the press-frame, which by means of registering apertures 56 of smaller diameter in the cylinder wall and the acidproof bushing 57 communicates with the explosion chamber 53. The firing mechanism is 75

carried by a collar 58 rotatably fitted upon the cylindrical portion 59 of the press-frame.

The collar is slotted as at 60, to afford access to the bore in the gland 55 in which the cartridge 54 is fitted so that the cartridge may be placed within the gland after the bore of the gland is exposed through the slot by rotary movement of the collar.

The collar 58 has a laterally projecting hollow boss 61 interiorly screw-threaded to receive a corresponding threaded holder 62 which carries the firing mechanism. This mechanism, as in the first described form of the invention, consists of a piston 63 slidably fitted in an axial bore of the holder, a screw plug 64 which closes the bore at its outer end, a stem 65 on the piston 63 extending through a central opening of the plug 64, a pin 66 on the piston movable through a small aperture at the end of the holder 62 to engage with the detonating cap of a cartridge inserted in the gland 55, and a compression spring 67 in the holder for forcing the firing pin into contact with the detonating cap. The piston stem 65 has, as before, a head 68 exteriorly of the plug 64, and an aperture 69 for the application of a cotter pin to hold the firing mechanism in an inoperative position, as shown in Figure 4.

Handles 70 at the outer end of the holder facilitate manual movement of the holder and the collar on which it is mounted. It will be apparent that after a cartridge has been inserted into the gland 55 through the slot 60 of the collar and the latter has been returned to its original position, the firing pin 66 is in alignment with the detonating cap of the cartridge to engage the same by expansion of the spring 67 after the piston has been released by withdrawal of the cotter-pin from the aperture of its stem.

A piston head 75 screwed as before into an interiorly threaded extension of the bore of the cylinder 49 of the press, has an axial bore in which a stem 71 of the before mentioned piston 52 is slidably fitted. The stem 71 has a longitudinal groove 72, and a set screw 73 on the head 45 projects into the groove, to hold the stem against rotation. Upon a threaded extension 74 of the stem above the piston head, is mounted a nut 76 with oppositely projecting handles 77. The nut has flattened sides 78 to permit of its moving downwardly into opposite slots 79 in the upper portion of the head, when it is turned into register therewith by means of the handles 77.

The piston 52 is beveled at its upper face to engage in a correspondingly beveled countersink 80 at the lower end of the head 75, and a copper washer 48a between the head 75 and the adjacent end of the bushing 57, seals the joint between these parts.

In the operation of a press of the modified construction, the work is, as in the press of the first described form, inserted between the legs of the frame through the opening at the lower end thereof. The anvil 44 is then placed between the legs and upon its seat in which position the tenons 45 in the corresponding grooves 46 prevent the legs from spreading apart. The nut 76 normally resting upon the head 75, is now turned so that its flat sides are in register with the slots 79, thereby permitting of downward movement of the piston 48 for the purpose of bringing the hammer 47 into contact with the coupling sleeve 81 on the anvil to press it firmly into the groove thereof. By the same movement, the taper-plug 51 is forced firmly into the taper bore or socket 50 of the piston 48.

The power-piston 48 is again raised by means of the handles 77 until the beveled face of the piston 52 engaging the bevel at the end of the head 75, and the parts are maintained in this position by turning the nut 76 at right angles out of register with the grooves 79 of the head.

The explosive cartridge is placed in the gland 55 through the slot of collar 58, after which the collar is turned by means of the handles 70 until the firing pin 66 is in alignment with the detonating cap at the end of the cartridge.

By means of the same handles the holder 62 may be screwed into contact with the gland 55 to provide a gas-tight joint. By drawing the piston 63 outwardly by means of the head 68 of its stem, the spring 67 is compressed to provide the impetus necessary to bring the firing pin into forcible contact with the detonating cap when the head is subsequently released. The consequent ignition of the explosive charge of 20 the cartridge generates intense pressure in the explosion chamber 53 with the result that the piston 48 is released from the taper plug 51, and driven downwardly to deliver a sudden and violent blow upon the coupling sleeve 81 on the 25 anvil. As a result of this action the sleeve and the conductors of electricity 82 are deformed and expanded as before, to permanently anchor the conductors within the sleeve in intimate conductive contact with the same.

It will be apparent that the taper plug 51 of the piston 52 firmly pressed into the corresponding socket 50 of the power-piston 48 holds the latter against operative motion until the explosive in the cartridge is completely burned and the maximum pressure is generated in the explosion chamber 53.

The connection between the stem 71 and the piston 48, by means of the taper plug 51 and the socket 50, also serves the purpose of returning 40 the hammer-piston back into its proper place with relation to the explosion chamber, after firing, thereby maintaining a uniform combustion chamber at all times.

What I claim and desire to secure by Letters 45 Patent is:

1. In a press of the character described, a frame having a cylinder, an anvil on the frame, a hammer piston in the cylinder to act upon work on the anvil, and a pressure member on the piston, adapted to subject the said work to pressure during action of the hammer to prevent the displacement of the work by said action.

2. In a press of the character described, a frame having a cylinder, an anvil on the frame, 55 a hammer piston in the cylinder to act upon work on the anvil, and a spring-pressed member on the piston, adapted to subject the said work to pressure during action of the hammer to prevent the displacement of the work by said action.

3. In a press of the character described, a frame having a cylinder, an anvil on the frame, a socketed hammer piston in the cylinder to engage with work on the anvil, a finger movable in the socket of the piston, to engage with work 65 acted on by the hammer to hold the same in place on the anvil, and a compression spring in the socket, acting on the finger.

4. In a press of the character described, a frame having a cylinder, an anvil on the frame, 70 a socketed hammer piston in the cylinder, to engage with work on the anvil, a finger movable in the socket of the piston, to engage with work on the anvil to hold the same in place, a helical spring in the socket, acting on the finger, and a 75

guide member on the piston to prevent lateral deformation of the spring.

5. In a press of the character described, a frame having a cylinder, an anvil on the frame, 5 and a hammer-piston in the cylinder having a contact-face slanting relative to a plane at right angles to the line of action of the hammer, to produce a correspondingly slanting indentation in a surface of the work engaged by the hammer.

10. 6. In a press of the character described, a frame having a cylinder, an anvil on the frame, and a hammer-piston in the cylinder having contact-faces slanting in opposite directions from the line of action of the hammer, to produce 15 correspondingly slanting indentations in surfaces of the work engaged by the hammer.

7. In a press of the character described, a frame having a cylinder, an anvil on the frame, a piston in the cylinder, a pressure-member on 20 the piston, adapted to engage with work on the anvil to hold the same in place, and a hammer at an end of the piston having contact faces to engage with the work at opposite sides of the pressure-member.

25. 8. In a press of the character described, a frame having a cylinder, an anvil on the frame, a piston in the cylinder, a pressure-member on the piston, adapted to engage with work on the anvil to hold the same in place, and a hammer 30 at an end of the piston having contact faces slanting oppositely from the pressure-member.

9. In a press of the character described, a frame having a cylinder, a shouldered bushing in the cylinder, a screw-head on the cylinder, engaging with the bushing, and providing an explosion-chamber in connection with the cylinder, firing mechanism for ignition of an explosive charge in the explosion chamber, an anvil on the frame, and a hammer-piston in the cylinder, 35 to engage with work on the anvil.

40. 10. In a press of the character described, a frame having a cylinder, and spaced legs at an end thereof, an anvil seated in the space between the legs, a flanged clamping-element embracing the ends of the legs, and wedge-members between the clamping-element and the legs to secure the anvil in place.

11. In a press of the character described, a frame having a cylinder, and spaced legs at an 50 end thereof, an anvil seated in the space between the legs, a flanged clamping-element embracing the ends of the legs, the element and the legs having complementary tapering grooves, and wedge-members in said grooves to secure 55 the anvil in place.

12. In a press of the character described, a frame having a cylinder, an anvil on the frame, a head for the cylinder, a hammer-piston in the cylinder, to engage with work on the anvil, and 60 spring-means to effect a contact between the piston and the head.

13. In a press of the character described, a frame having a cylinder, an anvil on the frame, a head for the cylinder, a hammer-piston in the cylinder, to engage with work on the anvil, a movable member on the piston, adapted to engage with the work to hold the same in place, and a compression spring acting upon the member and the piston, to force them in engagement 65 with work on the anvil and with the head, respectively.

14. In a press of the character described, a frame having a cylinder, an anvil on the frame, a head for the cylinder, a hammer-piston in the cylinder, to engage with work on the anvil, and 70

75 spring means adapted to effect a contact between the piston and the head by reaction upon work on the anvil.

15. In a press of the character described, a frame having a cylinder, an anvil on the frame, 5 a head for the cylinder, a hammer-piston in the cylinder, to engage with work on the anvil, and a spring to yieldingly oppose the power-stroke of the piston.

16. In a press of the character described, a frame having a cylinder, an anvil on the frame, a head for the cylinder, a hammer-piston in the cylinder, to engage with work on the anvil, and a spring to yieldingly oppose the power-stroke of the piston by reaction upon work on the anvil. 15

17. In a press of the character described, a frame having a cylinder, an anvil on the frame, a hammer-piston in the cylinder, to engage with work on the anvil, means to provide an explosion-chamber in connection with the cylinder and to hold an explosive charge in communication with the explosion-chamber, firing-mechanism for ignition of a charge in the explosion chamber, and means to manually move the hammer-piston in the cylinder. 25

18. In a press of the character described, a frame having a cylinder, an anvil on the frame, a hammer-piston in the cylinder, to engage with work on the anvil, means to provide an explosion-chamber in connection with the cylinder and to hold an explosive charge in communication with the explosion-chamber, firing-mechanism for ignition of a charge in the explosion-chamber, and manual means frictionally connecting with the hammer-piston for moving the same in the cylinder. 35

19. In a press of the character described, a frame having a cylinder, an anvil on the frame, a socketed hammer-piston in the cylinder to engage with work on the anvil, there being an expansion-space at an end of the hammer-piston, and a chamber to hold an explosive charge in communication with the expansion-space, firing-mechanism for ignition of a charge in the chamber, and an element having a taper-plug in the 40 socket of the hammer piston, and movable to manually move the piston in the cylinder. 45

20. In a press of the character described, a frame having a cylinder, an anvil on the frame, a hammer-piston in the cylinder to engage with work on the anvil, there being an expansion-space at an end of the hammer-piston, and a chamber to hold an explosive charge in communication with the expansion-space, firing-mechanism for ignition of a charge in the chamber, a head for the cylinder, an element movable 50 to the head, in frictional connection with the hammer-piston, and means for holding the element against sliding movement on the head, in one direction, whereby to permit of independent movement of the piston by the expansive force. 55

21. In a press of the character described, a frame having a cylinder, an anvil on the frame, a hammer-piston in the cylinder to engage with work on the anvil, there being an expansion-space at an end of the hammer-piston, and a chamber to hold an explosive charge in communication with the expansion-space, firing-mechanism for ignition of a charge in the chamber, a bored and slotted head for the cylinder, an element, including a stem slidable in the bore of the head, having a frictional connection with the hammer-piston, and a rotary nut on the stem adapted to support the element against inward movement, 70 75

in one position and to move inwardly through a slot of the head in another position.

22. In a press of the character described, a frame having a cylinder, an anvil on the frame, a socketed hammer-piston in the cylinder to engage with work on the anvil, a bored head for the cylinder, a piston in the cylinder normally seated against an end of the head, in spaced relation to the hammer-piston to provide an expansion-space, a chamber to hold an explosive charge, in communication with the expansion-space, firing mechanism for ignition of a charge in the chamber, a taper-plug on the piston, frictionally engaging in a socket of the hammer-piston, and a stem for the piston, slideable in the head.

23. In a press of the character described, a frame having a cylinder, an anvil on the frame, a socketed hammer-piston in the cylinder to engage with work on the anvil, a bored head for the cylinder, a piston normally seated against an end of the head and frictionally engaging the hammer-piston in spaced relation thereto, the space between the pistons constituting an expansion-chamber, a stem on the piston, slideable in the head, means to hold an explosive charge in communication with the explosion-chamber and firing mechanism for ignition of the charge.

24. In a press of the character described, a frame having a cylinder, an anvil on the frame, a socketed hammer-piston in the cylinder to engage with work on the anvil, a bored head for the cylinder, a piston in the cylinder normally seated against an end of the head and having a frictional connection with the hammer-piston, in spaced relation to the same whereby to provide an expansion-space, a chamber to hold an explosive charge, in communication with the expansion-space, firing mechanism to ignite a charge in the chamber, and a stem on the piston, slideable in the bore of the head.

25. In a press of the character described, a frame having a cylinder, an anvil on the frame, a hammer-piston in the cylinder, to engage with work on the anvil, there being an expansion space at an end of the piston, a gland on the frame providing a chamber for an explosive charge, in communication with the expansion space, a collar having a screw-threaded opening axially aligned with the chamber, a screw plug in said opening, in gas-tight contact with the gland, and firing mechanism on the screw-plug, in operative relation to a charge in the chamber.

26. In a press of the character described, a frame having a cylinder, an anvil on the frame, a hammer-piston in the cylinder, to engage with work on the anvil, there being an expansion space at an end of the piston, a gland on the frame providing a chamber for an explosive charge, in communication with the expansion space, a rotary collar on the frame having a screw-threaded opening normally aligned with the chamber and having a slot to expose the chamber in an adjusted position, a screw-plug in the opening of the collar, abutting against the gland in the normal position of the collar, and

firing mechanism on the plug, in operative relation to a charge in the chamber when the collar is in its normal position.

27. In a press of the character described, a frame having a cylinder, an anvil on the frame, a socketed hammer-piston in the cylinder to engage with work on the anvil, there being an expansion-space at an end of the hammer-piston, and a chamber to hold an explosive charge in communication with the expansion-space, firing mechanism for ignition of a charge in the chamber, a bored head for the cylinder having at the end of its bore, a countersunk seat, a second piston in the cylinder defining the expansion-space and having a beveled end normally 10 engaging the countersunk seat, a taper-plug at a side of the second piston, to frictionally engage in the socket of the hammer-piston, and a stem for the piston movable in the bore of the head.

28. In a press of the character described, a frame having a cylinder, an anvil on the frame, a hammer-piston in the cylinder, to engage with work on the anvil, there being an expansion space at an end of the hammer-piston, and a chamber to hold an explosive charge in communication with the expansion-space, firing-mechanism for ignition of a charge in the chamber, and an element connected with the hammer-piston to manually move the same to engage with work on the anvil, and to automatically release the same by movement of the hammer-piston by the expansive force.

29. In a press of the character described, a frame having a cylinder, an anvil on the frame, a hammer-piston in the cylinder to engage with work on the anvil, an element providing an expansion-space at an end of the hammer-piston, and having a frictional connection with the hammer-piston to manually move the same to engage with work on the anvil, there being a chamber for an explosive charge in communication with the expansion-space, and firing mechanism for ignition of a charge in the chamber.

30. In a press of the character described, a cylinder, an anvil, a hammer-piston in the cylinder to engage with work on the anvil, means providing an explosion-chamber in connection with the cylinder, and friction-means associated with the piston yieldingly opposing movement of the hammer during expansion of the ignited gases in the explosion chamber.

31. In a press of the character described, a cylinder, an anvil, a hammer-piston in the cylinder to engage with work on the anvil, means providing an explosion-chamber in connection with the cylinder, and friction-means associated with the piston comprising a tapered bore and a tapered plug insertable therein, yieldingly opposing movement of the piston during the initial expansion of the ignited gases in the explosion chamber.
